ROTARY TRANSFORMER

Giuseppe Massimo Pestarini, Sheffield, England

Application June 24, 1933, Serial No. 677,521
In Great Britain July 29, 1932

3 Claims. (CL 171—123)

This invention relates to rotary transformers for direct electric currents and to electric motor equipments operated in connection therewith. More particularly the invention relates to rotary 5 transformers of the type known as and herein-after called metadyne transformers which are machines designed to transform a current supplied thereto at a fixed voltage and variable amperes into a current at constant amperes and 10 variable voltage. A metadyne transformer comprises in general a rotor provided with windings and a commutator somewhat similar to the armature of a direct current dynamo electric machine. Four brushes are arranged to make contact with the commutator, two of which are used 15 for the primary circuit and two with the secondary circuit arranged in quadrature electrical relation with the primary brushes. The rotor is rotated at a constant speed in the magnetic field 20 which is due to the currents circulating in the rotor windings, a stator being provided which affords a return path of low magnetic resistance for the flux which is set up by the rotor currents. The stator is furnished with windings by which 25 various magnetic fluxes can be obtained which combine with the magnetic fluxes due to the primary and secondary currents circulating in the regulator and thereby regulate the electro-mechanical performance of the machine. For a 30 fuller description of metadyne transformers reference is directed to the specifications of French Patents No. 547,855, dated 25th February 1922, No. 623,438, dated 27th January 1926, and No. 637,946, dated 25th November 1926.

A description of the general construction and operation of metadyne transformers, generators and motors treated mathematically in considerable detail will also be found in a paper entitled "Essuisse sur la Metadyne" by G. M. Pestarini 35 in the Bulletin Scientifique A. I. M. No. 4 April 1931 of l'Association des Ingénieurs Electriciens, published by the Institut Electrotechnique Montefiore, Liège.

Metadyne transformers when operated at high 40 voltages, 1500 or 3000 volts for example, as commonly employed in electric locomotives, are liable to serious sparking at the commutator segments which may produce flash-overs and arcs from brush to brush resulting in damage to the commutator and brushes, and the chief object of the 45 present invention is to provide improved constructions which will avoid this objection.

According to the invention a metadyne transformer rotor is provided with two commutators, one or both of the primary brushes being associ-

ated with one commutator and one or both of the secondary brushes being associated with the other commutator in quadrature electrical relation to the primary brush set. The two commutators are connected to a single winding in which both the primary and secondary currents circulate. As the primary brushes are separated by a considerable distance from the secondary brushes liability to flash-over between these pairs of brushes is substantially eliminated. If a metadyne transformer is designed as a one-cycle machine, that is to say the same disposition of electrical elements and magnetic elements occurs only once in progressing through one complete turn round the rotor in the air gap between the 5 rotor and stator, the primary and secondary brushes will be located at opposite ends of different diameters of the machine at right angles to each other, thus further eliminating the liability to flash-over. With a multicycle machine 10 the diameters at the respective ends of which the primary and secondary brushes are located will not be perpendicular and the brushes will not be located so far apart as in a one-cycle machine. Otherwise the conditions are similar. The voltage 15 between two contiguous commutator segments in a metadyne transformer is furthermore less favourable to the occurrence of flash-overs than is the case with an ordinary dynamo machine. Such voltage between segments under 20 some conditions falls to zero, or may even be reversed. The commutators may be located at opposite ends of the machine, or in some cases flash guards may be provided on each commutator at the zone of commutation of the brushes 25 of the other commutator if desired.

Where the rotor is provided with a single winding and two commutators the primary brush which is connected to the high voltage terminal of the supply circuit may be associated with one 30 commutator and the other brushes, namely the other primary brush and the brushes by which current is conducted to and from the secondary circuit, associated with the second commutator, or in some cases one of the secondary brushes 35 may be associated with the same commutator as that with which the primary brush connected to the high voltage terminal of the supply is associated. In these cases it is clear that no flash-over 40 from the high voltage primary brush can reach 45 any point immediately connected to earth.

With metadyne transformers having two commutators as hereinabove described the load or consumption devices in the secondary circuit may be arranged across the secondary brushes which 50 55

are then connected in what is commonly termed a cross-connection. Where, however, the load is such as to be readily divisible into two parts, for example where it comprises a plurality of motors 5 which can be readily divided into two groups, one group may be connected between one primary brush and one secondary brush, and the other group connected between the other primary brush and the remaining secondary brush, this is commonly known as the figure-8 connection. When 10 the rotor has only one winding the figure-8 connection can only be used if the load is divisible into two substantially similar parts and it is preferable to employ some series field windings on 15 the motors in order to assist in maintaining stable conditions of the motors.

In order that the invention may be clearly understood it will now be described with reference to the accompanying drawing the figures of which 20 are electrical diagrams illustrating various methods of carrying out the same in practice.

In all the figures the rotor of a metadyne transformer is indicated at 1 and the stator at 2. The primary brushes are shown at 3 and 4, respectively connected to a source of current supply indicated by a trolley line T and to ground G, and the secondary brushes are shown at 5 and 6 and arranged in quadrature electrical relation to the primary brushes 1 and 2. The commutators associated with the rotor winding are indicated as 25 two concentric circles of segments 8 and 9. In Figs. 2, 4, and 5 the load in the secondary circuit is indicated as comprising two motors 10, 11 connected between the primary and secondary 30 brushes in the well known figure-8 connection, and in Figs. 1 and 3 the load, which in Fig. 1 comprises two motors 12 and 13 and in Fig. 3 comprises a single motor 14, is included between the secondary brushes in the well known cross- 35 connection.

In Fig. 1 the rotor 1 of the metadyne transformer has a single winding indicated at 20, and both the commutators 8 and 9 are connected to said winding. In this figure the motors 12 and 40 13 are shown as connected between the secondary brushes 5 and 6, and since they are connected in series through the rotor winding 20 it is unnecessary to provide series field windings in the motor 45 circuits.

Referring now to Fig. 2 the metadyne transformer is constructed in a similar manner to that shown in Fig. 1, but the motors 10 and 11 forming the load are arranged in figure-8 connection. It will be observed that current can flow through 50 each motor independently in a local circuit, for example through the motor 10, the primary brush 3 and secondary brush 5, which are connected through the rotor winding 20. The motors are therefore not strictly connected in series and it 55 is preferable to provide some field windings on the motors.

Referring now to Fig. 3 the rotor 1 of the transformer is provided with a winding 20 connected to the two commutators 8 and 9. Only one brush 60 3 is, however, associated with the commutator 8, the other primary brush 4 being associated with the commutator 9, with which also the secondary brushes 5 and 6 are associated. The load, indi-

cated as being a motor 14, is in this figure shown in cross connection.

In Fig. 4 the arrangements of the metadyne transformer are similar to those of Fig. 3 but the load is shown as comprising two motors 10 and 11 which are connected in figure-8 connection. 10

In Fig. 5 the rotor 1 of the transformer is provided with a winding 20, and one primary brush 3 and one secondary brush 5 are shown as being associated with the commutator 8 while the remaining primary brush 4 and secondary brush 6 are associated with the commutator 9. The load in this instance is shown as consisting of two motors 10 and 11, of which motor 10 is connected between the primary brush 3 and the secondary brush 5, the motor 11 being connected between the primary brush 4 and the secondary brush 6. The sense of rotation is preferably the one indicated by the arrow (counter-clockwise). With this disposition a flash-over starting from 20 the primary brush-set associated with the high voltage terminal cannot reach any other brush-set unless it makes $\frac{3}{4}$ of a complete revolution which is very improbable. 15

The fields of the motors in Figure 3 may be separately excited, either with or without series field windings but in the arrangements shown in Figs. 4 and 5 the motors are preferably provided with series field windings as in that shown in Figure 2. 25

I claim:

1. A rotary transformer having a rotor provided with a primary brush set and a secondary brush set located substantially in quadrature electrical relation with said primary brush set, one brush only of said primary brush set being associated with one of said commutators and being connected to a source of electrical supply, said other primary brush and said secondary brushes being associated with the other commutator, a load circuit, and means for connecting said load 3 circuit across said secondary brushes. 4

2. A rotary transformer having a rotor provided with a primary brush set and a secondary brush set located substantially in quadrature electrical relation with said primary brush set, one brush only of said primary brush set being associated with one of said commutators and being connected to a source of electrical supply, said other primary brush and said secondary brushes being associated with the other commutator, a load circuit, and means for connecting said load circuit across a pair of said brushes including a primary brush and a secondary brush. 4

3. A rotary transformer having a rotor provided with a winding associated with two commutators, a primary brush set and a secondary brush set electrically displaced from said primary brush set, a high voltage source of electrical power supply, means for connecting one brush of said primary brush set to said high voltage source of power supply, said one brush of said primary brush set being the only brush associated with one commutator, the next following brush in the sense of rotation being associated with the other commutator, and all other brushes being associated with said other commutator. 30
